UNITED STATES PATENT OFFICE.

ETHAN B. STANLEY, OF CINCINNATI, OHIO.

BRUSH-CLEANER.

1,069,350.

Specification of Letters Patent.

Patented Aug. 5, 1913.

Application filed January 13, 1912. Serial No. 671,135.

To all whom it may concern:

Be it known that I, ETHAN B. STANLEY, a citizen of the United States, residing at 2540 Madison road, Cincinnati, in the 5 county of Hamilton and State of Ohio, have invented certain new and useful Improvements in Brush-Cleaners, of which the following is a specification.

My improvement relates to sanitary brush 10 cleaners, and more particularly to a class employing mechanical cleaning means, together with sprays of hot water and steam under pressure, said hot water and steam being medicated if desired, together with a 15 drying arrangement.

The object is to provide a simple and 20 effective cleaning device for hair brushes, said device to form a part of the equipment of a barber or hair dressing establishment.

25 The device consists, broadly speaking, of a metal housing containing a roller yieldably and revolvably mounted beneath a comb, said comb being carried by a hollow perforated metal tubing, pivotally mounted and being connected with flushing means, together with a separate comb-cleaning and flushing means, and a suitable drier.

30 The form of my device here shown and described is at present preferred, but I wish it understood that I do not limit myself to this one form. I claim the right to modify the arrangement, size, material used, etc., as long as I do not depart from the spirit of the device as set forth in the claim here- 35 with attached.

In the drawings forming a part of this application—Figure 1 is a plan view. Fig. 2 is a sectional elevation of the interior mechanism taken on the line A—B of Fig. 1, 40 the housing thereof being partly broken away. Fig. 3 is a detail of the roller and comb portion partly in section. Fig. 4 is a plan view of the radiator or drier. Fig. 5 is a sectional view of the same.

45 In the preferred form of my device, described specifically, and the parts referred to numerically, 1 is a housing having openings 2 and 3, in which housing is yieldably and revolvably-mounted a roller 4, upon a 50 spindle 5; said spindle being carried by plungers 6 and 7, to which are attached compression springs, 8 and 9. A comb 10 is mounted above the roller and parallel to the same in a hollow tube 11, the said tube being 55 perforated as shown near where the

comb teeth enter, the whole being revolvably mounted in bearings 12 and 13 and being further provided with a collar 14 having shoulders 15 and 16 coöoperating with a limiting pin 17. The tube 11 is closed at the 60 end 18 and connected to a supply tube 19. An ordinary commercial four-way fitting 20 is disposed between tubes 19 and 25, and the remaining two right angle openings in the 65 said fitting carry short pieces of perforated tubing 21 and 22 closed at their far ends and located directly over a stiff bristled brush 23, the said brush being mounted on suitable supports 24. The supply pipe 25 passes through a hollow fluted radiating 70 means 26. At the rear end of the lowest point of the housing is a drain pipe 27, while a supporting means 28 is provided for the radiator.

The operation is as follows: The brush 75 is inserted between the comb and the roller with the back resting upon the latter. Further inward movement causes the comb to descend to the dotted position shown in the drawing and the bristles of the brush to 80 pass through the comb, thus removing the foreign matter from the brush and depositing the same on the outside of the comb. When the brush has been pushed in far enough to allow all the bristles to come in 85 contact with the comb, and it is being withdrawn, the comb is pushed up to the disengaging position (as shown in full lines in the drawing) by the removal of the brush, and the foreign matter remaining in the 90 comb is washed away by water spray flowing through the openings in the tubing in which the comb is mounted. (This occupies but a few seconds.) The brush may be inserted and withdrawn several times, being 95 flushed itself while passing through the comb, and may then be dried sufficiently upon the radiator at the side of the device, by several quick rubs over its fluted surface. The hair comb may be cleaned by 100 passing it over the stiff brush located in the device while the hot water is flowing from the sprinkler system located directly over the same.

By reason of the yieldable spring mountings of the roller brushes of any thickness 105 may be cleaned and the prongs of the comb allowed to sink to the inner surface of the back of the brush, thus eliminating the waste or foreign matter in the brush.

Having thus described my improvement,
I claim—

A brush cleaner consisting of a revoluble
yieldably mounted roller, a comb disposed
above and parallel to the same, a hollow
perforated tube revolvably mounted and car-
rying the said comb, means for limiting the
swinging movement of the said comb and
tube, flushing means connected to the said

perforated comb carrying tube, the whole 10
being located in a suitable housing, all as
and for the purpose shown.

In testimony whereof I affix my signa-
ture in the presence of two witnesses.

ETHAN B. STANLEY.
